JOHN EDDY CHACE, OF ADAMSDALE, MASSACHUSETTS.

BOTTLE CLOSURE.

Application filed July 7, 1927. Serial No. 204,008.

This invention relates generally to bottle closures, and has more particular reference to improvements in closures of that type commonly used for milk bottles and embodying a card board disk adapted to fit within the bottle mouth.

The primary object of the invention is to provide a simple and durable bottle closure of the above kind embodying a tab which is readily accessible for enabling removal of the closure from the mouth of the bottle with facility, and which is not likely to become torn or entirely detached from the closure disk in the pulling or removing operation.

Another object is to provide a bottle closure construction of the above kind in which the pulling tab is so provided and arranged as to enable ready and firm gripping thereof as well as providing a reliable means for facilitating removal of the closure disk from the bottle mouth.

A further object is to provide a bottle closure of the above kind which is simple and compact in construction, neat in appearance and capable of production at a nominal cost.

Still another object of the invention is to provide a milk bottle closure embodying a unit that includes a disk adapted to fit within the bottle mouth and provided with a pulling tab, and a cap member capable of ready detachment from said unit to expose the pulling tab of the latter whereby its subsequent removal from the bottle mouth may be effected, said cap member being shaped to fit over the mouth of the bottle for excluding the entrance of dirt and other foreign matter.

Still another object is to provide a bottle closure of the character specified in the preceding object wherein the cap member is provided with central and marginal portions disposed in the same horizontal plane, wherein the cap member has a depending annular flange or rim to engage around the external bead of the bottle mouth, and wherein the unit adapted to be fitted into the bottle mouth is provided with a depressed central portion whose lower surface is disposed in substantially the same horizontal plane as the lower free edge of the rim of the cap member, thereby enabling a plurality of the closures to be readily placed in superimposed non-resting relation, for ready successive feeding, one from under another, from the magazine of a bottle capping machine, as exemplified in my co-pending application, Serial Num-

ber 177,147, upon bottle cap, filed March 21, 1927.

Other objects will become apparent as the nature of the invention is better understood, and the same consists in the novel form, combination and arrangement of parts herein-after more fully described, shown in the accompanying drawings and claimed.

In the accompanying drawings, wherein like reference characters indicate corresponding parts throughout the several views,

Figure 1 is a top plan view of one form of milk bottle closure constructed in accordance with the present invention;

Figure 2 is a section upon line 2—2 of Figure 1, drawn upon an enlarged scale;

Figure 3 is a horizontal section upon line 3—3 of Figure 2, drawn upon a reduced scale;

Figure 4 is a view similar to Figure 1 of a modified form of the invention;

Figure 5 is an enlarged section on line 5—5 of Figure 4;

Figure 6 is a section on line 6—6 of Figure 5, drawn upon a reduced scale;

Figure 7 is a top plan view of another modified form of the invention;

Figure 8 is an enlarged section upon line 8—8 of Figure 7;

Figure 9 is a top plan view of still another form of the present invention substantially embodying the device of Figure 1 with an attached cap member adapted to fit over the bottle mouth;

Figure 10 is a section on line 10—10 of Figure 9;

Figure 11 is an enlarged section of the device shown in Figure 10 with the cap member detached but shown in operative relation with the unit adapted to fit within the bottle mouth, by dotted lines;

Figure 12 is a view similar to Figure 9 of still another form of the invention;

Figure 13 is an enlarged section taken upon line 13—13 of Figure 12;

Figure 14 is a horizontal section on line 14—14 of Figure 13, drawn on a reduced scale;

Figure 15 is a top plan view of a slight modification of the form of closure shown in Figure 1;

Figure 16 is an enlarged section taken on line 16—16 of Figure 15;

Figure 17 is an edge elevational view of the closure shown in Figure 15, applied to the mouth of a milk bottle, the free portion of

60

the upper disk being flexed upwardly, and a drinking straw being inserted through the bottom disk into the bottle to facilitate drinking of the contents of the latter;

5 Figure 18 is a view similar to Figure 15 showing a slightly modified form of the closure shown in the latter Figure;

Figure 19 is an enlarged section on line 19-19 of Figure 18; and

10 Figure 20 is a view similar to Figure 17, of the closure shown in Figure 18.

Referring more in detail to the drawings, each form of the invention illustrated embodies a unit adapted to be forced into and 15 to snugly fit within the mouth of a milk bottle in the usual well known manner, said unit in the present instances being composed of upper and lower disks 5 and 6, respectively, and, except in Figures 7 and 8, an

20 intermediate strip or sheet 7, disposed in contiguous relation with each other and permanently united at the central portions of the disks. The disks 5 and 6 are preferably of the same diameter, and these disks as well 25 as the sheet 7 are preferably formed of relatively stiff tough cardboard. While the disks 5 and 6 and sheet 7 may be secured together at points other than in the vicinity of the centers of the disks, they are entirely free

30 of connection with each other from a line adjacent but to one side of the centers of the disks as indicated by the dash line 8, to the adjacent side or edge portion of the closure or the left hand edge portions thereof

35 as viewed in Figures 1 and 4. In other words, the members 5, 6 and 7 are free of connection with each other from the line 8 to the edge portion 9 at least from the point 10 to the point 11, thus leaving the side portions 12 and 13 of the disk 5 and sheet 7, respectively, free to flex upwardly away from the lower or main closure disk 6. The upper disk 5 is cut

away at its free side so as to provide the same with a straight edge portion 14 parallel with the line 8, and integral with the adjacent edge portion of the sheet member 7 is an extension 15 which is folded upwardly around the edge 14 of the upper disk 5 and inwardly onto the adjacent upper surface portion of the latter, thereby forming a readily accessible tab for use in facilitating removal of the closure from the bottle mouth. In order to facilitate upward bending of the free portion 12 of the upper disk 5 on a line parallel with the edge 14 when the tab 15 is pulled, the disk 5 is scored or weakened on its under side as at 16 entirely across the disk member 5 on a line parallel with the edge portion 14 as shown more clearly in Figures 2 and 3 and 5 and 6. As this weakening line 16 is parallel with and adjacent the line of connection 8 between the members 5, 6 and 7, the bending of the free member 12 and 13 upwardly relative to the disk 6 along the straight line of weakening 16 is insured when

the tab 15 is pulled upwardly. When these free portions 12 and 13 flex upwardly a firm grip may be had upon the tab to reliably insure removal of the closure from the bottle mouth, and the pull is exerted near the center of the closure and in such manner that tearing of the tab from the body portion or sheet 7 thereof is rendered highly unlikely, especially in view of the stiff tough character of the latter.

75

As the tab 15 is formed part of a member entirely independent of the disks 5 and 6, the latter are not objectionably weakened as is the case in prior constructions wherein the tabs are stamped from the disks themselves. At the same time, the parts may be pressed into flat contiguous relation with the tab 15 normally flatly engaging the upper surface of the upper disk 5 so that a neat appearing compact closure is normally had.

85

In the form of the invention shown in Figures 1 to 3 inclusive, the disks 5 and 6 and sheet 7 are united by the use of a pair of staples 17 which are disposed in spaced relation and at opposite sides of the centers 90 of the disks with corresponding legs thereof in a plane intersected by the imaginary line 8.

95

In the construction shown in Figures 4 and 5, the disks 5 and 6 and sheet 7 are joined by adhesive between their contiguous faces, the adhesive being provided throughout these contiguous surfaces from the line 8 to the edge portions of the members 5, 6 and 7 remote from the free portions 12 and 13, the sheet 7 in this instance being also of substantially disk form and of the same diameter as the disks 5 and 6.

100

In the form of the invention shown in Figures 7 and 8, the closure simply consists of an upper disk 5^a and a lower disk 6^a united in contiguous relation by staples 17^a provided at opposite sides of and near the centers of the disks, and this leaves a portion of the upper disk 5^a free as indicated at 12^a from the weakening or score line 16^a to the adjacent edge portion 9^a of the disks. With this construction the intermediate member or sheet 7 is eliminated and a separate tab 15^a is provided upon the upper disk 5^a with 110 its outer end attached to the outer part of the free portion 12^a by means of a staple 18. As in the other forms of the invention, this construction of Figures 7 and 8 provides a free portion 12^a for the upper disk which is 115 free of connection with the adjacent portion of the lower disk and capable of readily flexing upwardly when the tab is pulled upwardly for removal of the closure from the bottle mouth.

120

In the form of the invention shown in Figures 9 to 11 inclusive, the unit of Figure 1 is attached by means of the staples 17 to the central depressed portion 19 of a cap member which has a marginal portion 20 and a 130

125

central part 21 whose upper surfaces lie in the same horizontal plane. The cap member is further provided with a depending continuous or annular marginal flange 22 adapted to fit around the external bead of the bottle mouth and to cooperate with the marginal portion 20 for excluding the entrance of dirt and other foreign matter into the mouth of the bottle. Further, the lower disk 6 is provided with a central depressed portion 23, the lower surface of which lies in substantially the same horizontal plane as the lower edge of flange 22, thereby enabling a plurality of the closures to be superimposed in non-nesting relation within the magazine of a bottle capping machine. This will insure against interference of one bottle cap with another disposed directly therebeneath, whereby the latter bottle cap may be readily fed from the magazine as is clearly explained in my above mentioned co-pending application. Further, the central part 21 is, in this form of the invention, provided by the upwardly pressed central portion of a separate disk whose margin 24 is fastened by adhesive to the adjacent marginal surface of the depressed portion 19 of the main member of the cap. With the unit of Figure 1 attached to the central portion 19 by means of the staples 17, the tab 15 will be firmly held between the cap member and the disk 5 so as to be held in folded operative position and normally concealed from view. An important feature of this form of the invention is that the cap member, including the portion 19 through which the staples 17 are extended and in engagement with which the ends of the staples are clinched, is formed of a relatively thin tender grade of pasteboard which will readily tear, the strength of the cap member being such as to permit the cap member to be readily torn loose from the staples 17 without effecting removal of the unit, embodying disks 5 and 6, from the bottle mouth. When the cap member is detached from this unit in this manner the tab 15 will be exposed and accessible as illustrated in Figure 11, whereupon the stopper unit may be readily pulled or removed from the mouth of the bottle. From the above description it is apparent that this form of the invention will provide a sanitary bottle closure in which the protective cap may be detached when no longer required, such as at a time after the bottled milk has been delivered to the consumer.

The form of the invention shown in Figures 12 to 14 is provided to accomplish the same purpose as that above described in connection with the form of the invention shown in Figures 9 to 11 inclusive. In this form of the invention shown in Figures 12 to 14 inclusive, the cap member has a flat top wall 25, and a depending marginal flange 26 adapted to fit around the external bead of the bottle mouth. In this way the marginal and central portions 20 and 21 are provided which are in the same horizontal plane, and the depressed central portion 23 of the lower disk 6 lies in the same horizontal plane as the lower edge of the rim or flange 26, whereby a plurality of the closures may be superimposed in non-nesting relation within the feed magazine of a bottle capping machine. However, in the present or last modification 75 of the invention, a separate disk is provided whose marginal portion 26 is secured by adhesive to the underside of the marginal portion of the cap member proper, and whose central portion is depressed as at 27, the stopper unit being secured to the depressed portion 27 by means of the staples 17. In this instance, the disk member having the depressed portion 27 is formed of relatively tender thin pasteboard through which the staples 17 will readily tear when the cap member is pulled upwardly, without effecting removal of the stopper element or unit from the bottle mouth. Thus, the same detachment of the cap member from the stopper unit is had as described above in connection with the form of the invention shown in Figures 9 to 11 inclusive, whereby the tab 15 is exposed for effective subsequent removal of the stopper unit from the bottle 95 mouth. In order to effectively prevent crushing of the depressed portion 27, the space between the bottom wall of the latter and the central portion 21 of the cap member proper is preferably filled by means of a suitable spacer means which may consist of one or more disks 28 of the required thickness and a lower ring member 29, between this spacer means and the bottom wall of the portion 27, within which sufficient clearance 105 is provided for the upper clinched ends of the staples 17. It will of course be appreciated that the stopper unit is disposed concentrically of and within the rim or marginal flange of the cap member in each of the forms of the invention shown respectively in Figures 9 to 11 inclusive and 12 to 14 inclusive. Further, in both instances, the tab 15 is firmly held between the depressed portion 19 or 27 of the cap and the adjacent free portion 12 of the upper disk 5.

The closure shown in Figures 15, 16 and 17 is the same as that illustrated in Figures 1 to 3 inclusive except that the lower disk 6 is provided with a small circular opening 120 therethrough as at 30 centrally of and directly beneath the upwardly flexible free portion 12 of the upper disk 5, of such size as to permit the free insertion of a conventional drinking "straw" 31 therethrough, whereby the straw 125 may be inserted in the milk bottle 32 while the closure is applied to the mouth of the latter for facilitating drinking of the contents of the bottle. Obviously, upon pulling upwardly upon the tab 15, the free portion 13 130

of the sheet member 7 and the free portion 12 of the upper disk 5 will be flexed upwardly away from the adjacent portion of the lower disk 6 so as to expose the opening 30 whereby the straw 31 may be inserted therethrough into the bottle 32, thus enabling drinking of the contents of the bottle while excluding the entrance of dirt and the like into the latter. The construction shown in Figures 18 to 20 inclusive is the same as that of Figures 15 to 17 inclusive except that the free portion 12 of the upper disk 5 is provided with a central notch 33 substantially conforming in size and shape to that of the shaft 15 and normally having the latter folded into the same so that its upper surface will lie flush with the upper surface of the upper disk 5. This represents a compact form of closure in which the tab is normally protected against accidental engagement or damage, and by making the notch 33 of slightly greater depth than the length of the tab 15, as shown in Figure 18, the end of the tab may be readily engaged for lifting the same out of the notch whereby it may be subsequently grasped for pulling the tab so as to flex the free portions 12 and 13 upwardly and also remove the closure from the mouth of the bottle if desired.

30 As the objects and manner of use of the several forms of the invention have been explained as the description progressed, it is believed that the manner of use and advantages of the invention will be readily understood and appreciated by those skilled in the art, without further detailed comment thereon.

Minor changes may be made without departing from the spirit and scope of the invention as claimed.

49 What I claim as new is:—

1. A milk bottle closure including upper and lower disks securely fastened together and adapted to fit within the mouth of the milk bottle, the upper disk being entirely free of connection with the lower disk at one side to define a free portion of said upper disk which is flexible upwardly away from said lower disk, an extracting tab attached to the closure and formed of a piece of material separate from the disks, said tab being disposed above the upper disk and associated with said free portion of the upper disk to cause upward flexing thereof when the tab is pulled to remove the closure from the bottle mouth, and a cap member attached at its central portion to the central portion of the upper disk and having a depending rim adapted to fit around the mouth of the milk bottle, said cap member being formed of sufficiently tender material as to permit tearing of the same from the upper disk to expose the tab and without removing the disks from the bottle mouth, and a cap member attached at its central portion to the central portion of the upper disk and having a depending rim adapted to fit around the mouth of the milk bottle, said cap member being formed of sufficiently tender material as to permit tearing of the same from the upper disk to expose the tab and without removing the disks from the bottle mouth.

2. A milk bottle closure including upper and lower disks securely fastened together

and adapted to fit within the mouth of the milk bottle, the upper disk being entirely free of connection with the lower disk at one side to define a free portion of said upper disk which is flexible upwardly away from said lower disk, an extracting tab attached to the closure and formed of a piece of material separate from the disks, said tab being disposed above the upper disk and associated with said free portion of the upper disk to cause upward flexing thereof when the tab is pulled to remove the closure from the bottle mouth, and a cap member attached at its central portion to the central portion of the upper disk and having a depending rim adapted to fit around the mouth of the milk bottle, said cap member being formed of sufficiently tender material as to permit tearing of the same from the upper disk to expose the tab and without removing the disks from the bottle mouth, the connection of the disks and cap member being effected by means of staples clinched therethrough.

3. A milk bottle closure including upper and lower disks securely fastened together and adapted to fit within the mouth of the milk bottle, the upper disk being entirely free of connection with the lower disk at one side to define a free portion of said upper disk which is flexible upwardly away from said lower disk, an extracting tab attached to the closure and formed of a piece of material separate from the disks, said tab being disposed above the upper disk and associated with said free portion of the upper disk to cause upward flexing thereof when the tab is pulled to remove the closure from the bottle mouth, a cap member attached at its central portion to the central portion of the upper disk and having a depending rim adapted to fit around the mouth of the milk bottle, said cap member being formed of sufficiently tender material as to permit tearing of the same from the upper disk to expose the tab and without removing the disks from the bottle mouth, the disks being arranged concentrically of and within the rim of said cap member, said cap member having a top wall with marginal and central portions in the same horizontal plane, and the lower disk having a depending central portion substantially flush with the lower edge of said rim of the cap member, whereby a plurality of the closures may be superimposed in non-nesting relation.

4. A milk bottle closure including upper and lower disks securely fastened together and adapted to fit within the mouth of the milk bottle, the upper disk being entirely free of connection with the lower disk at one side to define a free portion of said upper disk which is flexible upwardly away from said lower disk, an extracting tab attached to the closure and formed of a piece of material separate from the disks, said tab being

disposed above the upper disk and associated with said free portion of the upper disk to cause upward flexing thereof when the tab is pulled to remove the closure from the bottle mouth, a cap member attached at its central portion to the central portion of the upper disk and having a depending rim adapted to fit around the mouth of the milk bottle, said cap member being formed of sufficiently tender material as to permit tearing of the same from the upper disk to expose the tab and without removing the disks from the bottle mouth, the disks being arranged concentrically of and within the rim

of said cap member, said cap member having 15 a top wall with marginal and central portions in the same horizontal plane, and the lower disk having a depending central portion substantially flush with the lower edge of said rim of the cap member, whereby a 20 plurality of the closures may be superimposed in non-nesting relation, said cap member embodying a part having a depressed central portion to which the upper disk is attached. 25

In testimony whereof I affix my signature.

JOHN EDDY CHACE.
